UNITED STATES PATENT OFFICE

LYNUS CLYDE REYNOLDS, OF SWEETWATER, TENNESSEE

SHEET BINDER

Application filed January 21, 1927. Serial No. 162,622.

The present invention relates to devices for fastening sheets of paper or other material together, and aims to provide novel means for attaching sheets together in an extremely simple, convenient and effective manner, and which will eliminate the objections incident to the use of wire and sheet metal paper clips, staples, and similar fasteners.

Another object of the invention is the provision of a novel sticker capable of economical manufacture and adapted to be conveniently manipulated for moistening the sticker and applying it to the sheets so as to bind or fasten the sheets together in a desirable manner.

A further object of the invention is the provision of sheets of paper or other material having a sticker or binder applied thereto in a novel manner for fastening the sheets together.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a perspective view of the sticker or binder.

Fig. 2 is a plan view thereof showing same applied to the sheets, only portions of which are shown.

Fig. 3 is an edge view of the sheets with the sticker or binder thereon.

Fig. 4 is a plan view showing the sheets of Figs. 2 and 3 with an additional sheet added and having its corner portion folded back.

Fig. 5 is a plan view showing the sticker or binder used with sheets having slots therein.

Fig. 6 is an edge view of the sheets and sticker as shown in Fig. 5.

Fig. 7 is a perspective view illustrating a modified form of sticker.

The sticker or binder may be of paper, cloth or other suitable flexible material, and

may be of any suitable size and shape. As shown in Fig. 1, the sticker or binder 11 is formed from a rectangular piece of material, which may be cut from a strip of adhesive tape, and the sticker is doubled on the fold line 12 intermediate its ends to provide the wings or portions 13 and 14. The sticker is folded with the surface thereof containing the adhesive material brought together, but without moistening same, so that the wings 13 and 14 do not stick together. The wing 14 is folded away from the wing 13 on the fold line 15 parallel with the fold line 12, thereby opening the sticker and exposing the adhesive surfaces of the wings 13 and 14, with a doubled portion 16 formed by the folds 12 and 15, and located intermediate the ends of the sticker and at that side of the sticker opposite to the surface having the adhesive material thereon. The doubled portion 16, as well as the lower surfaces of the wings 13 and 14 are coated with the adhesive material, so that said doubled portion as well as the wings may be made to adhere to a sheet over which the sticker is placed. The portion 16 provides a convenient finger piece to be grasped between the thumb and forefinger for picking up or taking hold of the sticker and applying the adhesive surfaces of the wings 13 and 14 to a moistener or to the tongue.

By holding the sheets that are to be fastened together between the thumb and forefinger of one hand, the sticker may be picked up conveniently by the other hand and moistened, after which the sticker is readily placed astride the edges of the sheets, as seen in Figs. 2 and 3. The wings of the sticker are then pressed together which causes them to adhere to the opposite surfaces of the sheets 17. It will be noted that the sheets 17 are entirely detached from one another excepting along the corresponding edges thereof, and the sticker or binder 11 provides a hinge connection between the sheets in order that the sheets may be swung apart, thereby enabling the entire surface of the second or lower sheet to be exposed to view. The sticker or binder may also be of transparent material so as not to con-

ceal any written or printed matter on either sheet.

The stickers may be supplied in boxes or containers from which they may be readily removed by grasping the finger hold portions 16 thereof, for removing a sticker from a bulk supply and moistening the sticker and applying it to the sheets quickly and conveniently. The stickers may also be stacked, and it is possible to supply them one at a time for convenient removal by means of a dispenser or a machine for cutting and folding the stickers as used. The stickers may be supplied in bulk in various sizes, and a machine of small size may be provided to form and dispense the stickers ready for convenient removal and moistening. When a sticker is picked up with the portion 16 between the thumb and forefinger the sticker may be moistened and applied to the sheets without releasing the hold on the sticker, and by pressing the thumb and finger together the sticker is caused to adhere to the sheets, thus completing the operation quickly and conveniently, and in less time than would be required to apply a paper clip or fastener by hand.

A number of additional sheets may be added by using an additional sticker for each sheet. Thus, referring to Fig. 4 there is shown a third sheet 18 placed on the sheets 17, and a second sticker 11 is applied over the edges of the sheets 17 and 18. This may be repeated for additional sheets, and it will be noted that the sheets will all be hingedly connected together, with each sheet free excepting at the edge thereof. Moreover, any sheet may be torn out by cutting or tearing the corresponding sticker, inasmuch as each sheet is individually fastened to another sheet by the corresponding sticker or binder. A group or pad of sheets may thus be attached together, permitting the sheets to be swung apart, and enabling any sheet to be removed without separating the others.

Figs. 5 and 6 show the sticker used with sheets 19 having slots 20 cut or punched therein adjacent to and parallel with one edge. When the sticker has been moistened, one end thereof may be readily inserted through the slots 20, and the wings of the sticker pressed together after the ends of the sticker have been moved outwardly to project beyond the edge of the sheets, as seen in Figs. 5 and 6. The end portions of the sticker will thus adhere together, and will form a tab projecting beyond the edge of the sheets for convenience in lifting the group of sheets, such as from a file, or the tab may be used for index purposes. With this arrangement a single sticker may also be used for fastening together three or more sheets.

Fig. 7 illustrates a modified form of sticker or binder which has the intermediate fold 12' and the folds 15' at opposite sides thereof

forming the doubled portion 16' upstanding between and substantially perpendicular with the wings of the sticker, for convenience in grasping and holding the sticker. This form of sticker, however, requires more space than the sticker shown in Fig. 1, inasmuch as the first form of sticker may be packed substantially flat.

Having thus described the invention, what is claimed as new is:

A sticker having wings extending in opposite directions away from one another to bear on a surface and having a doubled portion between said wings forming a finger piece for convenience in picking up and manipulating the sticker, the inner surfaces of said doubled portion and the corresponding surfaces of both of said wings being coated with adhesive material, and the inner surfaces of said doubled portion being detached so as to slip over and adhere to the edge portion of a sheet.

In testimony whereof I hereunto affix my signature.

LYNUS CLYDE REYNOLDS.
